OSCILLATING PISTON ENGINE

John Moraway, San Francisco, Calif.

Application December 2, 1935, Serial No. 52,487

3 Claims. (Cl. 123—18)

The invention relates to an engine having a plurality of pistons which oscillate as a unit in a plurality of cylinders.

A general object is to provide an improved and simplified engine of the class described.

A more specific object is to provide an engine having four pistons which operate in pairs in arcuate cylinders which are separated by common cylinder head assemblies.

10 Another object is to provide cylinder head assemblies which provide valved intake and exhaust ports for the cylinders which terminate therat.

Another object is to provide for the ready and 15 independent placement and removal of the cylinder head assemblies.

An added object is to provide the features of present invention in an internal combustion engine.

20 The invention possesses other objects and features of advantage, some of which, with the foregoing, will be set forth or be apparent in the following description of a typical embodiment thereof, and in the accompanying drawings, in 25 which.

Figure 1 is a side elevation of an internal combustion engine embodying the features of the present invention.

Figure 2 is a plan view of the engine.

30 Figure 3 is a reverse side elevation of the engine.

Figure 4 is an edge view of the engine.

Figure 5 is a section at 5—5 in Figure 3.

35 Figure 6 is a section taken generally at 6—6 in Figure 4.

Figure 7 is a fragmentary section at 7—7 in Figure 1.

Figure 8 is a section at the broken line 8—8 in Figure 6.

40 Figure 9 is a section at the broken line 9—9 in Figure 6.

As particularly illustrated, the features of present invention are incorporated in the structure of an internal combustion engine 11 in which 45 four pistons 12 are provided by a unitary element 13 for oscillation in different portions of a torical bore 14 which is provided within an engine block of suitable structure. In the present structure the bore 14 is provided by and between complementary engine block sections 15 and 16 which are separable in the plane of the bore circle.

The cylinder bore 14 is particularly shown as being of circular cross-section, and is partitioned 50 by means of sector-shaped and removable cylin-

der head members 17 which are diametrically opposite each other in the cylinder circle to define bore portions of like length between them. The cylinder head members 17 provide cylinder ends for both bore portions, the faces of said 5 ends being shown as radial to the cylinder circle and perpendicular to the cylinder bore thereat. The pistons 12 are operative in the end parts of the bore portions whereby said parts comprise the cylinders 1 and 2 and 3 and 4 of the engine. 10

The element 13 comprises a central cylindrical hub 18 from which mutually aligned radial arms 19 extend, and said element will hereinafter be referred to as a rotor. Arcuate cross-members 21 of less cross-section than the cylinder bore are 15 carried at the extremities of the arms 19, and extend centrally within the said bore. The pistons 12 are carried at the extremities of the cross-members 21 in symmetrical arrangement with respect to the line of the arms 19. Said pistons are arranged to sealedly engage the cylinder bore 14 thereat and may be provided with sealing rings 22 for the purpose. As shown, the cross-members 21 and the arms 19 and the hub 18 and the pistons 12 comprise integral parts 25 of a one-piece structure whereby to provide a particularly simple rotor assembly.

The head ends of the pistons 12 are radial to the cylinder circle and perpendicular to the cylinder bore thereat whereby they may be substantially parallel to the cylinder ends when they are closely adjacent thereto. The spacing of the cylinder ends in the cylinder circle is understood to determine the oscillation range of the pistons between the head assemblies 17, and so of the 30 35 rotor. A cylindrical cavity 23 is defined within the engine block in coaxial relation with the rotor hub, and slots 24 extend between the cylinders and said cavity for receiving the rotor arms 19 therethrough to permit a full oscillation of 40 the rotor for alternately disposing the pistons carried by the arms at the different cylinder ends.

At its opposite ends, the rotor hub 18 is engaged in suitable anti-friction ring bearings 25 which externally engage in sockets 26 provided 45 for them in the block sections 15 and 16 whereby the rotor is centered between the block sections for oscillation about a fixed axis. A shaft 27 extends axially from the rotor hub 18, and through and from the block section 15, to provide a power connection for the rotor. The shaft 27 mounts a radial arm 28, and a connecting rod 29 extends from the free end of the arm 28 for swinging in a plane which is parallel to the plane of operation to the arm. A shaft 31 is 50 55

journalled in the engine block with its axis parallel to that of the rotor, and carries a gear 32 at one extremity thereof and adjacent the plane of swinging of the connecting rod 29 whereby an 5 end of the latter may be connected to a pin 33 which extends axially from the gear 32.

The connection provided between the rotor shaft 27 and the gear 32 is such that the oscillatory actuations of the rotor are arranged to 10 affect a rotation of the gear 32 in a constant direction, with the gear 32 having one complete revolution imposed on it for any two successive strokes of the pistons. It will be understood that the present arrangement is the operative 15 equivalent of a crank connection for the shaft 31 wherein the gear 32 provides the crank arm and the pin 33 is a crank pin. It will be noted that the present driving connection for the gear 32 also prevents a striking of the cylinder ends 20 by the pistons to determine the cylinder head clearance for the pistons.

The gear 32 meshes with a gear 34 which is carried on a shaft 35 journalled at the bottom of the engine block. Since in the present instance, the gear 34 extends below the engine 25 block, the latter is preferably mounted on a suitable frame base whereby the engine may overlie a supporting surface. As particularly illustrated, the intermediate base for the engine 30 comprises a pair of channel members 36 which are bolted to the block at its under side and extend in lines parallel to the rotor axis, it being noted that the shaft 35 and the rotor axis lie in the same vertical plane. The shaft 35 is 35 the power take-off shaft for the engine and may be suitably connected to a mechanism to be driven.

It will now be noted that the cylinder head assemblies 17 are engaged in radial openings which 40 extend through the engine block from the inner cavity 23 to the exterior of the block. Each said opening is defined between plane faces which are radial to the rotor axis and between mutually 45 parallel plane faces which are perpendicular to such axis. The assemblies 17 each comprise generally wedge-shaped members 37 which provide the cylinder end walls, and a wedge member 38 which is normally engaged between the members 37 to secure them in position. The cylinder end 50 faces are provided by relatively short cylindric extensions 39 of the members 37, said extensions fitting the bore thereat to determine a centered positioning of the members at the cylinder ends. The mutually opposed faces of the associated 55 pair of members 37 are planar for sliding and frictional engagement with complementary faces of the wedge 38; when the latter is forcibly engaged between the members 37 said members are positively secured in place.

60 Means are provided for releasably securing the head assemblies 17 in their appointed positions. The engine block cavity 23 is somewhat larger than the rotor hub 18 therein whereby an appreciable clearance space is defined about the hub, 65 and the means for fixing each head assembly 17 in place includes an anchor plate 41, which is arranged to engage the wall of the cavity 23 to span the inner end of the opening which receives the head assembly. The anchor plate 41 70 receives bolts 42 therethrough to extend outwardly therefrom and freely through bolt holes provided in the central planes of the wedges 38, and said bolts threadedly and removably carry nuts 44 at their outer ends for bearing engagement with the outer faces of the wedges. In this

75 manner, a tightening up of the nuts 44 on the bolts 42 is arranged to forcibly engage the wedge 48 between the head members 37 and so secure said members at the cylinder ends.

It will now be noted that the head members 5 17 provide the intake and exhaust passages for the cylinders. As is particularly brought out in Figures 4 and 6, each member 37 is provided with a valved passage 48 which extends transversely into it from the face of its portion 39 and thence 10 longitudinally therein to its outer face; in the present instance the passages 45 are exhaust ports. Valved passages 46 extend transversely through the members 37 to a connection with a T-shaped passage 47 which has its stem portion 15 extending longitudinally through the wedge 38 to the outer end thereof; the passages 46 and 47 jointly define an intake port for the cylinder ends at each cylinder head assembly. While such are not shown, it will be understood that 20 the exhaust and intake ports would be connected with suitable discharge and fuel supply ducts respectively.

As is particularly brought out in Figure 9, the valves 48 and 49 for the passages 45 and 25 46 respectively are of a slide type having cylindric bodies which slidably and sealedly engage in bores provided laterally through the members 37 and through the block section 16 in intersecting relation to the port passages 45 and 46. 30 Each valve body is circumferentially grooved whereby the registration of the groove with the port passage intersected by the valve is operative to open the passage. Springs 53 and 54 are constantly operative between the inner ends of 35 the valve bores and the valves 48 and 49 respectively to urge a disposal of the valves in an outward port-closing position; in this manner, the opening of a port at a valve requires an inward displacement of the valve against the resistance 40 of a spring. Valve stems 51 and 52 extend integrally from the valves 48 and 49 respectively, and outwardly of the cylinder block 16.

Means are provided for actuating the various 45 valves 48 and 49 to open the same at the proper times in an operative cycle for the various cylinders 1 to 4 inclusive. As particularly shown, brackets 55 and 56 extend integrally from the block section 16 and carry cam shafts 57 which mount generally oval cams 58 for constant peripheral engagement with the outer valve stem 50 ends. In the present instance, the engine 11 is of the internal combustion four-stroke cycle type, and the shafts 57 are accordingly arranged to be driven at one half the rate of the shaft 31, and 55 from the latter shaft.

As illustrated, the bracket 56 mounts a vertical shaft 59 which carries a bevel gear 61 for engagement with a bevel gear 62 on the shaft 31, the gear 61 having twice as many teeth as the gear 60 62. The shafts 57 mount bevel gears 63 which engage like-sized bevel gears 64 on the shaft 59 whereby the valve-operating cams 58 may be operative to displace the valves to open position in appropriate synchronism with the operative cycles of the pistons.

Means are provided for igniting explosive charges which have been compressed in the different cylinders, said means comprising spark plugs 66 of a usual structure which are connected 70 in an electric circuit which includes a suitable timer 67 whereby the compressed charges may be ignited at the appropriate time. As particularly illustrated, the timer 67 is mounted on the bracket for the direct operation of its rotary 75

member by the shaft 59. The spark plugs 66 are engaged in threaded openings provided through the block section 16 opposite the head ends of the various cylinders.

5 The engine block assembly which provides the cylinder bore 14 is shown as being generally cylindrical and may be cored out about said bore to provide a water jacket 68 therein. Threaded openings 69 and 70 at the top and bottom of the 10 block section 16 provide pipe connections for the circulation of a cooling fluid through the water jacket 68. Although such is not shown, it will be understood that a suitable system for lubricating the valves and cylinders and various bearings 15 would be provided in the operative engine.

It will now be noted that the various illustrations of the present engine show the various moving parts as disposed at mid-stroke for the pistons 12. By particular reference to Figure 6, 20 wherein a clockwise movement of the rotor is indicated, it will be noted that the firing order for the cylinders is 1-2-3-4, and the operative conditions in the cylinders are exhaust-intake-expansion-compression respectively; accordingly, the exhaust valve 48 is open for cylinder 1, the intake valve 49 is open for cylinder 2, and all the valves 48 and 49 are closed.

It will be understood that if the bevel gears 61 and 62 were of like size, the present engine 30 would be operable with a two stroke cycle. In the latter case, the engine might also be actuated with steam or compressed air, the ignition system being then omitted.

From the foregoing description taken in connection with the accompanying drawings, the advantages of the construction and method of operation will be readily understood by those skilled in the art to which the invention appertains. While I have described the features and the use of the device which I now consider to be a preferred embodiment of my invention, I desire to have it understood that the showing is primarily illustrative, and that such changes may be made as fall within the scope of the following 15 claims.

I claim:

1. A cylinder head structure for use in a toroidal cylinder engine of the oscillating piston type, wherein the head is disposed in a radial slot provided through the torus and having a side thereof defining a cylinder end, comprising a head member fittedly engaging said cylinder end to seal the cylinder bore thereat, a wedge member operative longitudinally in the slot and against the head member to secure the latter in its operative position, and releasable means directly coactive between the torus and the wedge member radially of the cylinder bore for disposing and securing the wedge member in its operative position. 5

2. A cylinder head structure for use in a toroidal cylinder engine of the oscillatory piston type, wherein the head is disposed in a radial slot provided in the torus and defining cylinder ends, comprising similar head members each fittedly engaging a said cylinder end to seal the cylinder 20 bore thereat and presenting flat and angularly related radial outer faces in mutual opposition, a wedge member complementarily fitting between said faces of the first members, and means directly cooperative between the torus and the wedge 25 member to dispose and releasably secure the wedge member in its operative position.

3. In a toroidal cylinder engine of the oscillatory piston type, an engine block having a torus portion thereof providing a torical cylinder bore 30 and a laterally continuous slot of rectangular cross-section extending radially through said torus in intersecting relation to the bore therein to define cylinder ends which are perpendicular to the line of the cylinder bore thereat, a wedgedly 35 tapered cylinder head member engaged in said slot with its angularly related faces in sealed engagement with the cylinder ends, and a tension bolt operatively engaging between the head member and a point of the torus at its inner side and 40 radially of in the line of the cylinder bore to urge and releasably maintain the operative engagement of the head member in the slot.

JOHN MORAWAY. 45
